APPARATUS FOR LIQUID TREATING OF FABRIC IN A FESTOON-LIKE ARRANGEMENT

August Jakob Brunner, Milan-Precotto, Italy

Application December 1, 1954, Serial No. 472,420

Claims priority, application Italy July 8, 1950.

10 Claims. (Cl. 68—158)

This invention relates to improvements in apparatus for liquid treating of fabric or similar material in a festoon-like arrangement, of the kind comprising a vat, a fabric delivery device adapted to deliver the fabric over a downward course and in a pendant state in said vat, a carrier consisting of an endless chain conveyor provided with supporting wooden members and a particular guide fast with said vat for said chain and said supporting members for obtaining relative displacements of the latter during the lengthwise motion of said conveyor.

Apparatus in which the festooned fabric is supported by a series of parallel wooden sticks or stoves having at their ends arms lying in the same radial plane and, freely pivoted, respectively, at their free ends in coaxial relation to the pivots of a pair of endless chains each moving along a path, a part of which is directed at right angles to the vertical plane along which the fabric is delivered to the vat is well known. The structure also includes at least one rail extending below and generally parallel with the upper stretches or runs of the endless chains, underlying said sticks and formed with a number of successive saw-tooth elevations, that cause repeated rising and falling of the sticks, which perform pendular movements upon advance of said chains. A repeated change in lines of contact of the liquid immersed sticks with the fabric is thereby obtained.

However, such an arrangement does not fully avoid forming of stick marks on the fabric treated, because the fabric can never be drawn away from the sticks, so as to become freely suspended in the treating liquid in the vat and thereby exposed to its action the zones of festoons which bear on said sticks during the travel of the fabric in the vat.

One object of the present invention is to provide an apparatus of the kind disclosed, fully avoiding the drawback mentioned above, and affording a very efficient action of the treating liquid in the vat on the fabric, while localized lapping or creasing of the latter in its contact zones with the sticks is fully avoided.

Another object of the invention is to provide, in connection with the apparatus of the type disclosed, an improved carrier for conveying the fabric in a festoon-like arrangement through the vat, which is of simple structure, easy to manufacture and low in cost, at the same time of high strength, as to be suitable for use in connection with the treatment of any type of fabric, including very heavy fabrics.

Another object of the invention is to provide a carrier by which the amount of passive resistances such as resistances due to friction is greatly reduced.

Another object of the invention is to arrange the carriers so as to mechanically produce a so called "lisage" effect, which is normally accomplished by the textile workers when treating the thread, fabrics or similar articles on the sticks.

The term "lisage" is used in the dyeing art to define the step which consists in rapidly moving, to and fro, the silk skeins supported on sticks resting by their ends on the edges of the vat containing the bath.

A further object of the invention is to provide in the apparatus an improved fabric festooning device adapted to cooperate with the fabric carrier and form fabric loops engaging the sticks supported by single links of the conveyor chains of the fabric carrier.

2

With this and other objects in view, the nature of this invention shall hereinafter be explained with reference to the appended drawings, in which:

Fig. 1 shows a longitudinal vertical sectional view of part of the whole improved apparatus adjacent its side at which fabric is delivered thereto.

Fig. 2 is a view on an enlarged scale, of a section of the carrier for the festooned fabric taken in a plane situated at right angles to the path of movement of its upper run.

Fig. 3 is a plan view of a part of the carrier shown in Fig. 2.

Fig. 4 is a side view of a structural detail of the carrier.

Fig. 5 is a perspective view, on an enlarged scale, of the details of the carrier illustrated in Figures 2 to 4.

Fig. 6 is an explanatory diagram showing diagrammatically the behaviour of the festooned fabric, when supported in the apparatus by means of the carrier shown in Figures 2 to 5.

Fig. 7 is a section similar to Fig. 2 of a modified embodiment of the carrier.

Fig. 8 is a plan view of part of the carrier embodiment shown in Fig. 7.

Fig. 9 is a side view of a structural detail of the modified carrier.

Fig. 10 is a section taken on line X—X of Fig. 9.

Fig. 11 is a section taken on line XI—XI of Fig. 9.

Fig. 12 is a side view of a detail of the carrier according to another modification.

Fig. 13 is a fragmentary perspective view of a part of a carrier according to this other modification.

Fig. 14 is an explanatory diagram showing diagrammatically the behaviour of the festooned fabric, when supported in the apparatus by means of the carrier modified as shown in Figures 12 and 13.

Figs. 15, 16 and 17 are diagrammatic views showing three successive stages of operation of the festooning device adapted to cooperate with the carrier made according to one of the preceding Figures 2 to 11.

Figs. 18, 19 and 20 are diagrammatic views showing three successive stages of operation of the festooning device adapted to cooperate with the carrier made according to one of the preceding Figures 11 to 14.

Fig. 21 is a perspective view of a detail of the carrier according to a modification of the latter.

Referring to the drawings wherein similar elements are denoted throughout the figures by the same reference numerals in which the numeral 1 denotes a vat containing treating liquid and 2 one of a pair of four pairs of sprocket wheels, each pair being mounted on a shaft 3 journaled in suitable bearings (not shown) in the fixed structure comprising the vat 1. Around the sprocket wheels 2 extend a pair of endless chains 4, the path of which generally comprises a substantially horizontal upper stretch or run and a lower stretch or run. The chains together form a carrier adapted to convey the fabric through the vat. Motor means (not shown) adapted to rotate one of the shafts 3, are provided in order to effect a length-wise movement of the chains in the direction shown by the arrow A in Fig. 1.

A liquid delivery or so called "cascade" device 5 is provided consisting of a tank subdivided by spaced upright walls 6 providing a hopper, the upper edge of which is subjacent to the upper end of the tank 5 and having a tapered bottom provided with a longitudinal slot-like outlet 7, so that the liquid overflowing the upper edges of the hopper can flow to the outlet 7.

The fabric F is delivered downwardly, as by a pair of suitably rotated rolls 8 and 9, to the tank 5 through an upper opening 10 and runs through the outlet 7 towards the carrier 4.

Treating liquid is continuously pumped into the tank of

5 of the cascade device at inlets 11 and leaves it through the hopper outlet 7 together with the fabric. A pendant partition 36 hinged at the hopper 6 near its outlet 7 and extending towards the carrier comprising the chains 4 is provided to form a festooning device.

Its purpose and manner of operation of the device will be hereinafter explained.

The width, taken in a plane perpendicular to that of Fig. 1, of the tank 5, more particularly of the slot 7 forming the outlet from the hopper is chosen so as to be substantially equal to the spacing between the chains 4 of the carrier.

The upper run of the carrier is arranged preferably below the level 13 of the liquid in the vat. The liquid can be withdrawn from the vat and returned to the cascade device.

The chains 4 of the carrier each comprise links pivoted together at equally spaced intervals as at 14.

Alternate links (Figs. 2, 3 and 4) of each chain consist of pairs of parallel spaced inner plates 15a and 15b, aligned for each chain along inner and outer rows, respectively, and of pairs of parallel outer plates 16a and 16b, aligned for each chain along inner and outer rows, respectively. The pairs of plates 15a, 15b are hinged to the plates 16a and 16b overlapping the former at their lower region by means of coaxial pivots 17a, 17b formed at the opposite ends of the cylindrical pivots 18, of greater diameter, which are coaxial therewith and also act as a spacer for the plates 15a, 15b and 16a, 16b at their lower zones. Pivots 19 linking the upper zones of said plates act at the same time as spacers, so that correct spacing of the plates in the direction of the width of the carrier is constantly insured.

Obviously, the pivots could be of any other suitable form, as they are no characteristic feature of the invention. All the plates forming the links of the chain are generally arranged in planes perpendicular to the planes containing the axes of the coaxial pivots 17a and 17b connecting subsequent plates of each row.

Both chains are so arranged that during the operation of the carrier the pivots 18 connecting their links are constantly coaxial and aligned as closely as possible.

All plates are substantially of the same outer shape. However, the plates of each chain appertaining to the inner rows are formed with longitudinal slots 20, extending in each plate with the slot axis perpendicular to the plane containing the axes of the pivots 18 connecting said plate with the plates of the adjacent row, and lying in the transverse plane of symmetry of said plate.

The slots 20 in the plates 15a, 15b of one chain are obviously aligned with the slots in the corresponding plates of the other chain, and receive the flattened end portions 21 of a series of sticks or wooden members 22 intended to support or carry the loops L of the festooned fabric as the latter travels through the vat. The end portions 21 of the members 22 are slidably mounted in the slots 20, so that said wooden members may be raised and lowered with respect to the chain links. The intermediate portions 22C of the wooden members 22 are circular in cross section, and can be made tubular in order to reduce their weight. Alternatively, they can be made elliptical in cross section, in order to increase their strength against bending when loaded with loops of heavy fabric or other material of great weight.

Obviously, they may be tubular along their whole length and have a diameter suited to the width of the slots 20.

They can be made tubular and be provided with apertures, as an intermediate portion 122C, in their wall in order to reduce the contact surface between said wall and the fabric and thus allow wetting of the latter by the treating liquid along said contact surface (see Fig. 21).

This structure is convenient in cases when highly sensitive fabrics or material are treated, which are sensitive to contact with smooth surface.

The chains 4 are supported and guided along their upper stretches or runs by suitable guide and supporting means, such as plates 23 secured to angle irons 24 fast with the side walls 25 of the vat 1, and flat irons 26 secured to said walls and insuring a correct clearance between the walls and the chains 4.

Saw-toothed vertical guides or rails 27 of sheet metal are provided and these are of suitable thickness extending parallel with each chain 4 adjacent thereto and substantially along the whole upper stretch of said chains.

The guides 27 are secured to angle irons 24, as by welding, by means of horizontally bent portions 27'.

The upper edges of said guides 27 are of a saw-toothed profile comprising sloping rectilinear edges or surfaces 28, horizontal top surfaces 29, vertical surfaces 30 and horizontal bottom surfaces 31 following one another. The guides are arranged in the vat with their profiles aligned and constantly engaging the intermediate portions of the wooden supports 22 near the zones at which the flattened portion of the latter begins. This arrangement of the guides and slots in the links of both chains causes during the operation of the apparatus, that is, during travelling of the pendant fabric loops, hanging downwardly from the supports through the vat, repeated gradual raising thereof followed by sudden dropping of the wooden supports with consequent temporary floating of the fabric loops free from the 3 supports in the treatment liquid as clearly shown in Fig. 6.

The efficiency of the bath is thereby considerably increased and the period during which the fabric is in contact with the supports with the danger of forming stick marks on the fabric, is reduced. In fact, due to the upward hydrostatic thrust, the fabric slowly follows the downward movement of the sticks or supports and is taken up by them only after the latter have travelled a considerable way over the next sloping portions of the saw-toothed guides.

The profile of the guides can obviously be other than shown on the drawings, provided it causes the sticks to perform a movement of the character described.

Finally, the slots 20 may be replaced by other equivalent means, such as upright or vertical bars engaging forks or eyes provided at the ends of the supports, in order to allow vertical displacements of the latter when they engage the upper edges of the guides.

In order to allow use of supports of equal length the inner faces of the plates 16b have secured thereto by means of point welding, lugs 32 equalling in width the plates 15b and facing the slots 20 provided in plates 16a. The lugs may be formed from the material left when cutting the slots 20 in plates 15a and 16a.

In order to avoid the necessity of welding of the lugs 32 to the outer plates 16b, which is rather elaborate and expensive, the links can be made as shown in Figures 7 to 11. In this case the links of each chain comprise outer plates 116a and 116b formed with upright projections 133a and 133b, which are in the form of plates bent with respect to the plates 116a and 116b, so as to be aligned with the rows of inner plates 115a and 115b. The projections 133a are provided with slots 120.

Fig. 12 shows an embodiment of the chain according to which the plates 215a and 216a, that is, the plates pertaining to the inner rows of plates of each chain, are each provided with two parallel slots 220, whereby each of said plates engages the flattened end portions of two adjacent supports.

In this case any loop of fabric is supported by two successive wooden supports close to each other. The above mentioned effect of "lisage" is thereby mechanically obtained as clearly shown in Figure 14.

The manner in which the fabric is folded to form loops or festoons depending freely from the supports within the treatment liquid contained in the vat, will now be explained.

As shown in Fig. 1, each of the guides 27 is formed

at its end situated at the zone of the vat subjacent the outlet 7 from the delivery or cascade device, with a portion 34 along which its upper edge extends horizontally, whereby all the sticks or supports conveyed along said zone are arranged substantially with their axes lying in a common horizontal plane. The hopper 6 carries hinged thereto at 35, near its outlet 7 a depending plate 36 (Figs. 15 to 20), the dimension of which measured in a plane perpendicular to the plane of the drawing, equals at least the length of the outlet slot 7. The length of said plate is such that it may be engaged by the flanks of the successive wooden supports (that is, their intermediate portions 22C) upon their advancement in the direction of the arrow A.

The manner in which loops or festoons of the fabric are suspended on successive sticks will be clearly understood from Figures 15, 16 and 17.

The fabric F issues through the outlet 7 of the hopper under the action of the mass of the liquid leaving the latter. When the plate 36 is in a vertical position (Fig. 15) the fabric moves downwardly within the treatment bath in the vat. On advancement of the supports 22 (Fig. 16) in the direction of the arrow A, the plate is carried along as its lower edge 37 touching the flank or leading face of a support 22 as shown.

The liquid and fabric issuing from the outlet 7 slide over the plate 36 and flow downwardly ahead of the support 22. This arrangement is advantageous inasmuch as it promotes even stretching of the fabric and prevents creases from being formed at the next stage, which begins when the lower edge 37 of the plate 36 is disengaged from the support 22. The plate then rapidly resumes its vertical position (Fig. 17) as it is displaced by the thrust of the liquid and fabric sliding on the plate. This sudden oscillation of the plate sets up a suction effect which assists in forming the fabric loop superimposed on the next or following wooden support 22.

It is clear that such an arrangement absolutely prevents bridging two or more supports by the same loop of fabric.

Obviously, the length of the outlet or slot 7 is smaller than the spacing of the opposed saw-toothed guides 27, the looping being due to the fact that the downfall of the fabric is faster than the advance of the carrier bearing the wooden support.

When bridging of the two supporting members by the loops of fabric is desired, an arrangement shown in Figures 18, 19 and 20 may be employed.

As will be seen from said figures, in order to bridge two successive supporting members 22 by a loop of fabric, it may be sufficient for the alternate wooden support members 22 to be arranged with their axes relatively shifted in a vertical direction as they move along the edge or surface 34 of the guides 27, and for the length of the depending plate 36 to be such that its lower edge never engages the lower supports 22a but engages the leading face of the upper support member 22b.

The manner in which this feature can be carried out in practice can be seen in Fig. 13.

The flattened portions 21 of the supporting or carrying members are made higher than their intermediate portions 22C and on alternate members they are long enough (in an axial direction of the members) to engage by their lower edges 21a the upper edges of the saw-toothed guides 27. As the remaining wooden carrying members engage the guides by their intermediate portions, a vertical shifting of the axes of alternate carrying members will be obtained.

The use of the depending plate 36 in connection with the forming of loops not only permits of suspending them to a determined number of sticks, but also prevents forming of creases at the point of contact between the fabric and sticks.

What I claim is:

1. In an apparatus for liquid treatment of fabric or similar material in a festoon-like arrangement and in

which the fabric is delivered over a downward course, comprising a vat for containing a treatment bath, a carrier for the fabric consisting of two endless chains, the path of which generally defines a substantially horizontal upper stretch and a lower stretch, each comprising a series of equal links pivoted to one another, means for moving both chains lengthwise in the same direction with the pivots of one chain aligned with the pivots of the other chain, a series of supporting sticks for the fabric loops movable lengthwise with the carrier, parallel to one another, each supported at its opposed ends by the aligned links of said chains, means being provided for allowing relative displacement of said sticks with respect to their supporting links only in a direction perpendicular to the planes containing the axes of the two subsequent pivots connecting said links with other adjacent links, two stationary saw-toothed guides in said vat being further provided, extending parallel with the upper stretch of said chains, arranged between the latter, each engaging by its upper edge the end portions of said sticks at the region at which they engage the aligned links of the chains, whereby during travelling of the fabric loops through the vat repeated gradual rising followed by sudden falling of the sticks with consequent temporary floating of said loops in the treatment liquid contained in the vat take place.

2. In an apparatus for liquid treatment of fabric or similar material in a festoon-like arrangement and in which the fabric is delivered over a downward course, comprising a vat for containing a treatment bath, a carrier for the fabric consisting of two endless chains, the path of which generally defines a substantially horizontal upper stretch and a lower stretch, each comprising a series of equal links pivoted to one another, means for moving both chains lengthwise in the same direction with the pivots of one chain aligned with the pivots of the other chain, a series of supporting sticks for the fabric loops movable lengthwise with the carrier, parallel to one another, each supported at its opposed ends by the aligned links of said chains, said links having upstanding portions each provided with at least one slot perpendicular to the plane containing the axes of the two subsequent pivots, the slots of the aligned links of the two chains being also aligned and receiving the end portions of the sticks which are slidably mounted therein, means being provided for preventing an axial displacement of each stick with respect to its supporting links, two stationary saw-toothed guides in said vat being further provided, extending parallel with the upper stretch of said chains, arranged between the latter, each engaging by its upper edge the end portions of said sticks at the region at which they engage the aligned links of the chains, whereby during travelling of the fabric loops through the vat repeated gradual rising followed by sudden falling of the sticks with consequent temporary floating of said loops in the treatment liquid contained in the vat take place.

3. In an apparatus for liquid treating of fabric or similar material in a fastoon-like arrangement and in which the fabric is delivered over a downward course, comprising a vat for containing a treatment vat, a carrier for the fabric consisting of two endless chains the path of which generally defines a substantially horizontal upper stretch and a lower stretch, each comprising a series of equal links pivoted to one another, means for moving both chains lengthwise in the same direction with the pivots of one chain aligned with the pivots of the other chain, a series of supporting sticks for the fabric loops movable lengthwise with the carrier, parallel with each other and each supported at its opposed ends by the aligned links of the said chains, said links having upstanding portions provided with at least one slot perpendicular to the plane containing axes of the two subsequent pivots connecting said links with other adjacent links, all slots being of the same width and equally spaced along each chain and the slots of the aligned links of the two chains being also

aligned and the end portions of the sticks which are slidably mounted therein, means being provided for preventing axial displacement of each stick with respect to its supporting links, two stationary saw-toothed guides in said vat being further provided, extending parallel with the upper stretch of said chains, arranged between the latter, each engaging by its upper edge the end portions of said sticks at the region at which they engage the aligned links of the chains, whereby during travelling of the fabric loops through the vat repeated gradual rising followed by sudden falling of the sticks with consequent temporary floating of said loops in the treatment liquid contained in the vat take place.

4. In an apparatus for liquid treating of fabric or similar material in a festoon-like arrangement and in which the fabric is delivered over a downward course, comprising a vat for containing a treatment vat, a carrier for the fabric consisting of two endless chains the path of which generally defines a substantially horizontal upper stretch and a lower stretch, each comprising a series of equal links pivoted to one another, means for moving both chains lengthwise in the same direction with the pivots of one chain aligned with the pivots of the other chain, alternate links of said chains consisting of pairs of parallel spaced inner plates and pairs of parallel spaced outer plates, said pairs of outer plates overlapping the adjacent pairs of inner plates and being hinged thereto by means of pivots, said plates being arranged in planes perpendicular to the planes containing the axes of two subsequent pivots connecting said links with other adjacent links, the inner and outer plates of each chain facing the inside of the vat being each provided with at least one slot perpendicular to said plane containing the axes of the subsequent pivots connecting said links with other adjacent links, the slots in the aligned links of the two chains being also aligned, means for maintaining the plates of each link in spaced relationship, a series of supporting sticks for the fabric loops movable lengthwise with the carrier engaging by its opposed ends the slots facing each other in said two chains, two stationary saw-toothed guides in said vat being further provided, extending parallel with the upper stretch of said chains, arranged between the latter, each engaging by its upper edge the end portions of said sticks at the region at which they engage the aligned links of the chains, whereby during travelling of the fabric loops through the vat repeated gradual rising followed by sudden falling of the sticks with consequent temporary floating of said loops in the treatment liquid contained in the vat take place.

5. Apparatus for liquid treating of fabric or similar material in a festoon-like arrangement and in which the fabric is delivered over a downward course as according to claim 4, wherein the length of the sticks is substantially the distance between the outer plates of the links of one chain and the outer plates of the links of the other chain, and in which said outer plates are provided with fixed lugs substantially equal in width to the width of said inner plates, said lugs being positioned facing the slots engaged by the ends of said sticks, whereby all the sticks are of substantially the same length and axial movement of said sticks is substantially prevented.

6. Apparatus for liquid treating of fabric or similar material in a festoon-like arrangement and in which the fabric is delivered over a downward course as set forth in claim 2, wherein the sticks are provided with flattened end portions engaging the slots cut in aligned links of the two chains.

7. Apparatus for liquid treating of fabric or similar material in a festoon-like arrangement and in which the fabric is delivered over a downward course as set forth in claim 2, wherein the sticks are provided with flattened end portions engaging the slots provided in aligned links of the two chains, and wherein the saw-toothed guides

are arranged to engage the zones of the sticks immediately preceding said flattened portions.

8. Apparatus for liquid treating of fabric or similar material in a festoon-like arrangement and in which the fabric is delivered over a downward course as set forth in claim 2, wherein the sticks are provided with flattened end portions engaging the slots cut in aligned links of the two chains, and wherein the saw-toothed guides are arranged to engage the lower edges of said flattened portions, which are offset with respect to the surface of the intermediate portions of the sticks.

9. Apparatus for liquid treating of fabric or similar material in a festoon-like arrangement and in which the fabric is delivered over a downward course as set forth in claim 4, wherein in the inner and outer plates of each chain facing the inner and outer plates of the other chain are provided with two slots symmetrically disposed with respect to the transverse planes of symmetry of said plates, and wherein the sticks are formed with flattened end portions engaging said slots in said plates, the axial length of said flattened portions on alternate sticks being such that they engage the upper edge of the saw-toothed guide by the lower edges of said flattened end portions and by the lowest part of their intermediate portions, respectively, whereby the alternate sticks lie with their axes at different levels when they engage a horizontal portion of the saw-toothed guide.

10. In an apparatus for liquid treating of fabric or similar material in a festoon-like arrangement and in which the fabric is delivered over a downward course, comprising a vat for containing a treatment vat, a carrier for the fabric consisting of two endless chains the path of which generally defines a substantially horizontal upper stretch and a lower stretch, each comprising a series of equal links pivoted to one another, means for moving both chains lengthwise in the same direction with the pivots of one chain aligned with the pivots of the other chain, alternate links of said chains consisting of pairs of parallel spaced inner plates and pairs of parallel spaced outer plates overlapping by their ends the ends of adjacent pairs of inner plates and hinged thereto by means of pivots, said plates having upstanding projections arranged in planes perpendicular to the planes containing the axes of subsequent pivots connecting said links with other adjacent links, said projections of the inner and outer plates of each chain being provided with at least one slot perpendicular to said plane containing the axes of subsequent pivots connecting said links with other adjacent links, the projections on the outer plates of each link being such as to be aligned with the projections on the inner plates of the same chains, the slots in the aligned links of the two chains being also aligned, means for maintaining the plates of each link in spaced relationship, a series of supporting sticks for the fabric loops movable lengthwise with the carrier engaging by its opposed ends the slots facing each other in said two chains, two stationary saw-toothed guides in said vat being further provided, extending parallel with the upper stretch of said chains, arranged between the latter, each engaging by its upper edge the end portions of said sticks at the region at which they engage the aligned links of the chains, whereby during travelling of the fabric loops through the vat repeated gradual rising followed by sudden falling of the sticks with consequent temporary floating of said loops in the treatment liquid contained in the vat take place.
